UNITED STATES PATENT OFFICE

154,688

DESIGN FOR A GEARED HEAD FLUID MOTOR WITH SPEED CONTROL

Onnie A. Lind, Columbus, Ohio, assignor to The
Denison Engineering Company, Columbus,
Ohio, a corporation of Ohio

Application January 3, 1947, Serial No. 135,914

Term of patent 14 years

(Cl. D55—1)

To all whom it may concern:

Be it known that I, Onnie A. Lind, a citizen of the United States, residing at 358 Blenheim Road, Columbus, in the county of Franklin and State of Ohio, have invented a new, original, and ornamental Design for a Geared Head Fluid Motor With Speed Control, of which the following is a specification, reference being had to the accompanying drawing, forming a part thereof, in which:

Figure 1 is a perspective view on an enlarged scale of a geared fluid motor with speed control, showing my new design; and

Figure 2 is a side elevational view thereof; and

Figure 3 is a top plan view.

I claim:

The ornamental design for a geared head fluid motor with speed control, substantially as shown.

ONNIE A. LIND.
